UNITED STATES PATENT OFFICE.

PIET VLAG, OF WEST TAMPA, FLORIDA.

ORCHARD HEATER.

Application filed August 25, 1923. Serial No. 659,422.

To all whom it may concern:

Be it known that I, PIET VLAG, of West Tampa, county of Hillsborough, and State of Florida, have invented certain new and useful Improvements in Orchard Heaters; and I do hereby declare the following to be a full, clear, and exact description of the invention, such as will enable others skilled in the art to which it appertains to make 10 and use the same.

My invention relates to orchard heaters, and it is intended to provide improvements in efficiency and economy of operation, and simplicity and economy of construction over 15 the types of orchard heaters now generally in use.

The present application is a continuation, in part, of my prior application, Serial No. 594,260, filed October 13, 1922.

20 The invention relates more particularly to heaters of that type in which liquid fuel is used as distinguished from those in which wood, coal or other solid fuel is employed.

The invention moreover is not intended to 25 throw off any smoke, and therefore is distinguished from the smudge type of apparatus for protecting orchards against freezing weather.

In apparatus using liquid fuel it is especially desirable, both for fuel economy and 30 efficiency of operation, to have the combustion as complete as possible; also it is desirable for the products of combustion to be scattered over the ground at a low level so that they may occupy as shallow a stratum 35 of air as possible, as any heat carried by the ascending gases above the tops of the trees is practically wasted.

It is well known that the products of incomplete combustion of liquid fuel contain 40 more or less carbon monoxide (CO), which is lighter than air and tends to rise, and in producing which not near so much heat is generated as in the production of carbon dioxide (CO₂) which is heavier than air and 45 would normally tend to descend. Of course, when the combustion is complete, the products of combustion will consist mainly of nitrogen, from which the oxygen has been removed, mixed with carbon dioxide, both 50 of which are heavier than air, and more or less aqueous vapor which is lighter than air. The tendency of this mixture when released 55 would be to rise in the air, but in cold weather this aqueous vapor is soon condensed into water, delivering its latent heat to the

surrounding atmosphere, and the nitrogen and carbon dioxide are cooled by contact with the atmosphere and would tend to remain at a low level. Therefore, if the products of combustion are delivered close to the surface of the ground they will spread along the ground and rise slowly in the orchard, thus economically distributing the heat where most needed.

65 My invention is especially intended to accomplish these results.

A further feature important in such apparatus is to prevent the liquid fuel from becoming mixed with rain water, and therefore it is important to keep the device practically rain-proof. Furthermore, it is important to render the device efficient in strong winds which, with the apparatus now generally used, are apt to interfere with the 70 proper operation of the device by creating air currents which interfere with the efficient operation of the heater.

75 A still further object of this invention is to so proportion the sizes of the various parts; such as the height and diameter of the chimney, the size of the combustion chamber, and the size and location of the air feeding and distributing cone, as to produce 80 all of the above advantages, and insure complete combustion and elimination of carbon.

85 Finally, it is important to have the apparatus of simple and light construction which may be conveniently transported when desired, and may be conveniently set up or taken apart and operated as required.

It will be obvious that such apparatus is liable to be of infrequent use and should be so constructed as not to require any special attention when stored away and not 90 in use, and not likely to get out of order.

I have endeavored to construct the apparatus so as to cover all of the desirable features hereinbefore described.

95 My invention will be more fully understood after reference to the accompanying drawings, in which like parts are indicated by similar reference symbols throughout the several views, and in which:—

100 Figure 1 is a front elevation of the complete apparatus, parts being shown in section and parts broken away.

105 Figure 2 is a plan view of the annular bowl or tank in which the liquid fuel is placed, the cone and flare, and the upper 110 portion of the apparatus being removed from said tank.

Figure 3 is a view of the device shown in Fig. 2, as seen from the left of said figure.

Figure 4 shows a section along the line 4-4 of Fig. 3 and looking down.

5 Figure 5 is a detail view of the distributing cone and flare used in the apparatus.

Figure 6 is a detail showing the deflecting cap removed from the apparatus; and

10 Figure 7 shows the top of the smoke stack provided with the protecting cap which should be kept over the top of the smoke stack when the heater is in the open and not in use. This cap is mainly intended to keep out rain and dust when the heater is not in

15 use.

The apparatus comprises a bowl A, preferably made of annular construction and provided on the interior with a central air flue A° to supply the air needed in burning the 20 fuel. This bowl is shown as provided near its top with an annular bead α connected with the main body of the bowl by the annular flange α' which thus forms an overhanging structure, as shown most clearly in 25 Figs. 1 and 3. This bowl may be mounted on any convenient support, such as the legs B, spaced apart as shown in Fig. 1, so as to permit the free passage of air beneath the bowl. Bricks or blocks of any kind may be substituted 30 for the legs if desired, provided the bottom of the bowl is raised above the ground far enough to permit the free passage of air into the air flue A°.

35 Mounted above the bowl is the conical skirt C having its lower portion c adapted to fit snugly over the bead α of the bowl A, and having its upper portion cylindrical as at c' to engage the smoke stack D. The upper end of the skirt C is open as at c' .

40 The smoke stack D is normally closed when not in use by the cap E, see Fig. 7, but when the heater is in operation it is provided with an umbrella-shaped cap F which may be detachably connected to the smoke stack as by means of the resilient legs f, see 45 Figs. 1 and 6. These legs serve to space the umbrella cap a suitable distance above the smoke stack, so as to permit the free passage of the products of combustion beneath the umbrella cap, and the shape of said cap tends to deflect the products of combustion downwards.

50 Mounted over the air flue A° is the perforated cone H. The lower portion h of said cone is not perforated and serves as a flare, as will be hereinafter described. This cone is connected to the walls of the air flue A° by means of the resilient legs h' , see Figs. 1 and 5.

55 The ignition is started and controlled by means of the damper I, see Fig. 3. This damper may be provided with a thumb lug or handle i, and is shown as having an opening i' to uncover one or more of the three 60 holes 1, 2 and 3, varying progressively in

size, formed in the side of the bowl, as shown in Figs. 1 and 3, and the damper may be drawn out to permit the influx of air through either the smaller hole 1 of the two holes 1 and 2, or the three holes 1, 2 and 3. 70 The rate of combustion of the liquid fuel will obviously be increased according to the amount of air permitted to flow in through one or more of these holes just referred to. This damper and the openings controlled thereby, it will be noted, are mounted beneath the overhanging shoulder α' and are thus protected against rainfall. 75

To prevent side winds from interfering with the operation of the device, I provide 80 a deflecting strip K, which, if desired, may be of corrugated form as shown in Fig. 4, and this deflector projects down into the liquid fuel abreast the holes 1, 2 and 3, as shown most clearly in Figs. 1 and 2. Adjacent to the damper I, I provide a shelf M having openings m therein on which shelf a small piece of cotton waste or the like saturated with kerosene may be placed for convenience in starting the ignition. This shelf 85 M may be made integral with the deflector K, if desired, and removable therewith from the apparatus. 90

The success of this orchard heater depends 95 not only on the novel combination and construction of the above described parts, but also on the relative positioning of the parts and the relative sizes thereof. Experimentation has proven that the lower row of openings in the cone H should be below the chimney D substantially two-thirds of the distance between the chimney D and the surface level of the fuel in the bowl A, and that the diameter of the cone H at the lower openings should be about six-sevenths of the diameter of the chimney D. Also, the height of the chimney D must be substantially nine times the diameter thereof to insure proper draft and complete combustion at the desired height about the cone H. 100

105 The operation of the device is as follows: Suppose the parts to be assembled and in the position shown in Fig. 1, with the bowl charged with liquid fuel, the waste lighter in place, and the damper open, insert a lighted match or a torch through the opening 3 of the damper; this will ignite the waste and the flame will be distributed around the entire surface of the liquid fuel. Any suitable liquid fuel may be used, preferably crude distillate of mineral oil, such as kerosene; but probably no oil of a lower specific gravity than 28 Baumé should be used, or not higher than 45 Baumé. 115

120 The initial combustion will develop a mixture of vapors from the surface of the oil which is rich in carbon and nitrogen, but lacking in oxygen, and the combustion will be incomplete; but after reaching the flare and passing over the perforations in the 130

cone the supply of oxygen from the air coming in through the air flue A^o will be more than sufficient to complete the combustion, and this combustion will take place in the form of a flame rising up through the smoke stack. As soon as the apparatus is working properly the damper is set to the desired opening, depending upon the amount of heat derived from the heater.

10 The products of combustion pass up through the smoke stack and striking the umbrella cap F are deflected downwards towards the ground, and mingle at the same time with the surrounding atmosphere. The 15 hot gases striking the colder air outside will become more or less chilled and most of the aqueous vapor will be converted into water, releasing the latent heat of said vapor, which latent heat will be distributed through the 20 surrounding air, and would naturally cause the gaseous particles to rise; but the lighter aqueous vapor being removed and the heavier gases, nitrogen and carbon dioxide, then predominating, the tendency of the heated 25 gases to rise would be in a measure compensated for, and the resultant gases would then form a blanket, so to speak, over the face of the ground extending upwards amongst the trees. The more perfect the combustion, 30 the heavier will these gases be, and therefore the tendency of the heated gases to rise will by a large measure be compensated for, if not overcome.

By having a large number of these heaters 35 scattered through the orchard and simultaneously in operation, the heat may be distributed very widely over the orchard and the trees protected from excessive cold.

It will be obvious that the umbrella cap 40 F will prevent rain from falling down the smoke stack, and the protected position of the damper I will prevent rain water from entering through the slot in the side of the bowl.

45 The deflector K is used to prevent any strong wind, blowing in at that side of the bowl, from interfering with the normal operation of the device, since air thus blown in by the wind would strike this deflector and 50 would be so scattered or distributed that it would not interfere with the proper process of initial ignition. Moreover the cone and flare being entirely protected from the external air currents would be free from the usual 55 objectionable eddy currents which take place when the surplus air is admitted, through the sides of the smoke stack. Thus it will be seen that all of the operative parts of the heater are substantially screened, either from 60 wind or rain, and operated internally in the device.

With the apparatus herein described a large quantity of air is supplied, not only to support combustion but to be heated and 65 distributed from the heater with other prod-

ucts of combustion in a low stratum where the most economical results are secured.

By having an excess of oxygen present, and having a strong up draft through the smoke stack, the combustion is complete, 70 there is little or no smoke produced and there is practically no carbonization or clogging up of the smoke stack or of the burner attached thereto. This obviates the necessity of frequent cleaning out of the apparatus 75 which is very important, as these devices are only intended for infrequent use and then may have to be used continuously for a considerable time, and it is important to have them kept in such continuous use without being overhauled for cleaning or repairs.

Where a slow heat is required the damper is only opened so as to expose one or more of the small holes while if a strong heat is required all of the holes of the damper are exposed. The fuel burns very much longer, 85 of course, when the initial combustion is small than where it is great, and the heat derived from the heater is of course much larger when a greater supply of fuel is used. 90 The amount of fuel used can therefore be controlled by regulating the damper. The fuel burns gradually down from the surface towards the bottom of the bowl until it is entirely consumed. 95

The heater may be conveniently recharged by taking off the smoke stack and pouring into the bowl a fresh supply of liquid fuel. This of course should not be done when the bowl is hot. 100

It will be obvious that various modifications might be made in the herein described apparatus, and in the construction, combination and arrangement of parts which could be used without departing from the spirit of my invention, and I do not mean to limit the invention to such details except as particularly pointed out in the claims. 105

The various parts of the apparatus may be made of cheap rolled steel or the like, and the complete apparatus will be quite light and may be easily transported either in the assembled or in the knock-down condition. It will thus be seen that I provide a cheap, 110 simple, efficient and economical device which 115 may be used for the purpose.

Having thus described my invention, what I claim and desire to secure by Letters Patent of the United States is:

1. An orchard heater comprising a bowl 120 for containing liquid fuel and having an air flue extending up through the body of fuel, a perforated cone having its apex closed, said cone seated upon the upper end of the air flue above the body of lubricant, a conical skirt upon the bowl concentric with said cone, said skirt enclosing an uninterrupted conical chamber extending between the perforated cone walls and the skirt, said conical chamber being directly above the fuel 125 130

body, and an elongated chimney upon the upper and smaller end of the skirt.

2. An orchard heater comprising a bowl for liquid fuel supported at an elevation and having an air flue extending up centrally therethrough, a cone closed at its apex and fitted over the upper end of said flue, spring arms carried by the interior of said cone for slipping into said flue, said cone being perforated, a conical skirt removably seated on said bowl and being concentric with the perforated cone, said skirt adapted to enclose a conical space uninterrupted from the perforated cone to the skirt and said space extending above the body of the fuel, said space being wider at its base and being gradually restricted upwardly toward the point of the cone and the upper end of the skirt, and a relatively high chimney on the upper end of said skirt.

3. An orchard heater comprising a bowl adapted to contain a quantity of fuel and having a central flue extending up through the body of the bowl, a chimney spaced above the bowl, a cone seated over the top of the air flue and having a closed apex and a plurality of openings in its side with the lowermost openings spaced below the chimney substantially two-thirds of the entire distance between the chimney and the surface level of the fuel, the diameter of the cone at the lowermost openings thereof being substantially four-fifths of the diameter of the chimney, and the height of the chimney being substantially nine times the diameter of the chimney, and a skirt between the chimney and the bowl enclosing said cone and providing a combustion chamber thereabout and between the lower row of openings and the apex of the cone.

4. An orchard heater comprising a bowl

adapted to contain a quantity of fuel and having a central flue extending up through the body of the bowl, a chimney spaced above the bowl, a cone seated over the top of the air flue and having a closed apex and a plurality of openings in its side with the diameter of the cone at the lowermost openings equal substantially to six-sevenths of the diameter of the chimney, the diameter of the cone at the lowermost openings thereof being substantially four-fifths of the diameter of the chimney, and the height of the chimney being substantially nine times the diameter of the chimney, and a skirt between the chimney and the bowl enclosing said cone and providing a combustion chamber thereabout and between the lower row of openings and the apex of the cone.

5. An orchard heater comprising a bowl adapted to contain a quantity of fuel and having a central flue extending up through the body of the bowl, a chimney spaced above the bowl, a cone seated over the top of the air flue and having a closed apex and a plurality of openings in its side with the lowermost openings spaced below the chimney, substantially two-thirds of the entire distance between the chimney and the surface level of the fuel, the diameter of the cone at the lowermost openings thereof being substantially four-fifths of the diameter of the chimney, and the height of the chimney being substantially nine times the diameter of the chimney, and a skirt between the chimney and the bowl enclosing said cone and providing a combustion chamber thereabout and between the lower row of openings and the apex of the cone, the diameter of said cone at the lowermost openings being equal substantially to six-sevenths of the diameter of the chimney.

PIET VLAG.
